LIPSTICK KIT

Seymour D. Wassyng, Great Neck, Long Island, N.Y., assignor to Clairol Incorporated, New York, N.Y., a corporation of Delaware

Filed Aug. 16, 1965, Ser. No. 86,586

Term of patent 14 years

(Cl. D86—10)

Fig. 1.

Fig. 2.

Fig. 3.

Fig.4.

Fig.6.

FIGURE 1 is a perspective view of a lipstick kit showing my new design, a lipstick being removed from the holder for the purpose of illustration;

I claim:

The ornamental design for a lipstick kit as shown and described.
